DISPENSER FOR CUPS

Clark D. Sims, Huntington Station, N.Y., assignor to Owens-Illinois, Inc., a corporation of Ohio

Filed Jan. 31, 1969, Ser. No. 15,578

Term of patent 14 years

Int. Cl. D9—99

U.S. Cl. D52—2

FIG. 1

FIG. 2

FIG. 3

FIG. 1 is a front elevational view of a cup dispenser showing my new design;

FIG. 2 is a right side elevational view thereof;

FIG. 3 is a top plan view thereof;

FIG. 4 is a rear side elevational view thereof;

FIG. 5 is a left side elevational view thereof;

FIG. 6 is a bottom plan view thereof; and

FIG. 7 is an enlarged sectional view, along lines 7—7 of FIG. 3.

I claim:

The ornamental design for a dispenser for cups, substantially as shown.
